UNITED STATES PATENT OFFICE.

JOHN B. SEMPLE, OF SEWICKLEY, PENNSYLVANIA.

PROJECTILE.

1,172,636.

Specification of Letters Patent.

Patented Feb. 22, 1916.

Application filed January 29, 1915. Serial No. 5,022.

To all whom it may concern:

Be it known that I, JOHN B. SEMPLE, residing at Sewickley, in the county of Allegheny and State of Pennsylvania, a citizen 5 of the United States, have invented or discovered certain new and useful Improvements in Projectiles, of which improvements the following is a specification.

My invention relates to improvements in 10 projectiles. It is illustrated in the accompanying drawings, in which—

Figure 1 is a view in longitudinal central section of the posterior end of a projectile in which my present invention is embodied; 15 Fig. 2 is a view in cross-section of the fuse-stock of the projectile of Fig. 1, the plane of section being indicated in Fig. 1 by the line II—II; and Fig. 3 is a view in section of a locking block in detail in one specific per- 20 missible form.

In a co-pending application, Serial No. 835,131, filed April 29, 1914, and allowed August 5, 1914, I have described and claimed a projectile including in its structure a movable member controlling detonation in this 25 respect: When this movable member is in one position and the detonator explodes, detonation will not be imparted to the burster charge; but when the movable member is in its alternate position, explosion of the detonator will result in communication of detonation to the burster charge. One specific 30 alternative means of accomplishing this end is illustrated and described in the application referred to and specifically claimed in the more limited claims of that application. That specific means includes in the structure 35 a burster charge and a detonator charge movable the one with respect to the other from remote to adjacent position—the object being that, in case of premature explosion 40 of the detonator (which in the present state of the art consists of unstable and dangerous material), the burster charge will be safe from explosion; but, when once the projectile is fired from a gun, the conditions incident 45 to firing and flight will bring detonator and burster charge into relative positions for service; so that, when upon impact the detonator is exploded in proper and intended manner, explosion of the burster 50 charge will follow in regular course.

My present invention is another specific means of accomplishing the same ends. Or, 55 in other words, it is another specific inven-

tion under the same generic invention noted above. My present invention, like my earlier invention referred to, employs a movable member, and this movable member is controlled in the same manner as in the 60 earlier case; but in this case the detonator is stationary, and the movable member (instead of carrying the detonator from remote position to a position of operative proximity to the burster charge) serves to control 65 the continuity of a path of detonation transmission, from detonator to burster charge, and in its movement to carry a section in a train of detonation. Normally, and until the projectile has been fired, this train is interrupted; as the projectile is fired from a 70 gun and flies through the air this train is made continuous; so that, whereas before firing explosion of the detonator will be without effect upon the burster charge, after 75 the projectile has been fired from a rifled gun the ensuing explosion of the detonator will be imparted in intended manner to the burster charge. Among the advantages of 80 this arrangement over the specific arrangement described in detail in my earlier application, referred to, are these: The problem how best to arrange the detonator with its adjacent safety chamber is simplified by the elimination of one factor. Again, the detonator being stationary, whatever liability 85 to miss fire may be inherent in the traveling detonator is avoided; premature detonation of the burster-charge is more certainly guarded against. Finally, as compared with 90 a runway for a movable detonator (which must be straight and relatively large) the detonation pathway from a stationary detonator to the burster charge may be 95 small and (if for other reasons desirable) may be tortuous.

Detonation is a phenomenon which certain substances exhibit, of exploding, under proper conditions, with extraordinary intensity. A mass of black powder explodes 100 progressively. The chemical changes advance from the point at which the impulse is applied to the remote portions of the mass; and, though this progression is a very rapid one, it is still a clearly discernible 105 progression. When a mass of picric acid, by way of comparison, is detonated, the chemical breaking down and rearrangement of elements (which presumably must be progressive also) advances with such swift- 110

ness throughout the mass that the whole body seems to have been resolved instantaneously; the progression is so rapid that it cannot be detected. Furthermore, detonation of such a substance as picric acid is a phenomenon of enormously greater power and intensity than the explosion of a like quantity of black powder. Substances so characterized are in common speech classed 10 as "high explosives"; their distinguishing characteristic is their ability to detonate.

Some substances capable of detonation are, under all ordinary conditions, quite inert and harmless; so true is this that certain of them were long known to the useful arts because of other properties and characteristics, while their explosive nature remained quite undiscovered. The substances of which I am speaking may be 15 handled with safety; no ordinary shock explodes them; they are combustible; some of them may on ignition be exploded in a low-power explosion—an explosion of second magnitude—but none of them can be exploded in an explosion of first magnitude—*i. e.* detonated—on ignition. The flash of a percussion cap, such as is ordinarily used to fire the burster charge of an explosive projectile, has no power upon them to effect 20 detonation. They can be detonated only by submitting them to shocks of great intensity—indeed only by the detonation of an adjacent body of high explosive. In this class of materials, the class of normally inert high explosives, are picric acid and its derivatives, tri-nitro-toluene, and tetra-nitro-anilin. These and other substances of 25 like characteristics have of late years come into general use as materials for the burster 30 charges of explosive projectiles. There are certain other high explosives—and the number available is small—which possess this peculiarity: they detonate on ignition. Fulminate of mercury is such a substance; lead 35 nitrid is another. These substances are not practicable as material for the burster 40 charges of projectiles; they are too sensitive; the danger incident to handling them in large quantities forbids. But though not 45 available as burster-charge material, these substances become serviceable in the manufacture of explosive projectiles, because of 50 their peculiar property mentioned; their use is indeed indispensable in producing practically 55 operative explosive projectiles charged with such a material as tetra-nitro-anilin, for example. That material is not responsive to the flash of a percussion cap; or, at 60 least, it cannot be detonated, as a charge of black powder is exploded, by the flash of a 65 percussion cap. By introducing into the make-up of a projectile a body of such material as fulminate of mercury and by placing it in intermediate position, where it will be subjected to the flash of a percussion cap

properly fired and where it is in detonation-imparting relation to the burster charge proper, a high-explosive shell may be produced. The intermediate charge of fulminate need not be, and for obvious reasons 70 will not be, large. When then means are provided which normally prevent the transmission of the impulse of detonation from the charge of fulminate to the burster charge (so that in case of premature and accidental detonation of the sensitive fulminate 75 the burster charge will not be detonated) but means which allow such transmission when the proper time has come, it is manifest that a practical high-explosive shell has 80 been produced.

Various expedients have been adopted to keep the fulminate charge (commonly called the "detonator charge" or "detonator") and the burster charge normally separate 85 and to bring them into detonation-imparting relation at the proper time. These prior expedients, so far as I am aware, have involved the provision of a movable detonator which may advance in a runway from a remote and relatively harmless position to a 90 position where, on firing, it will impart detonation to the burster charge. And of course, in such an arrangement, provision is made for the proper control of the detonator in its movement.

Now my present invention, while in one aspect it stands related as I have said as species to genus to an earlier invention involving a movable detonator, in another aspect is characterized by this: It does not require that detonator and burster charge be relatively movable. It consists, essentially, in arranging detonator and burster charge at a suitable interval, in providing a 100 pathway for detonation transmission from one to the other, and in supplying means for alternately and at proper times interrupting that pathway and making it continuous.

Detonation is a very different thing from the flash of a percussion cap. A flash is, essentially, a flame—a body of incandescent gas—which, proceeding from its source, may travel across wide air spaces and through 115 long empty ducts; detonation is a force, an impulse, a vibration, like electricity, and is communicated through suitable bodies—which are, indeed, "conductors" of detonation. A flash will leap through a passage- 120 way; detonation has no such power. In a manner analogous to the leaping of a spark across an air gap in an electric circuit, detonation will leap across an air gap if the "tension" be great enough; but, under conditions such as are here contemplated, detonation will hardly leap through a passage way which is longer than its own diameter. Generally speaking, detonation is imparted through contact. On the other hand, det- 125

onation may be freely carried for indefinite distance, if only the material through which it is carried be proper and be substantially continuous in extent; and ordinarily it will be true, and as I now practice my invention it is true, that the pathway which in my projectile I provide for detonation transmission would not afford passage of the flash of a primer cap nor transmit its effect.

In the accompanying drawings 1 indicates a burster-charge chamber within the projectile, and 2 a fuse stock for the fuse which is to detonate the burster charge within chamber 1. B is a booster charge, that is, a reinforcing charge, intended to receive detonation from the detonator and to impart detonation to the charge within chamber 1. This, under existing practice, will ordinarily consist of tri-nitro-toluene or similar material. For all present purposes, booster B is part of the burster charge and will in this specification be so considered. D is the detonator charge (consisting usually of fulminate of mercury) arranged, it will be observed, at a distance from burster charge B, separated therefrom by heavy walls. The detonator fits snugly within a cylindrical chamber, and this chamber is conveniently arranged centrally within a vacant safety chamber 14. In case of premature firing of the detonator the gases of explosion will fill chamber 14 but (the parts about to be described being in safety position) the explosion will have no effect upon the burster charge. It is further to be observed that the safety chamber 14 is a closed chamber within the fuse stock and when the parts are assembled within the body of the projectile. Since it is a closed chamber there can be no danger, in case of the premature firing of the detonator, of the spitting out of flame and gas and of the attendant danger to life and limb of those who have to do with the handling of these articles.

A pathway 13 for detonation transmission leads from the cylindrical chamber in which detonator D snugly fits to the chamber containing the burster charge B. This pathway may be direct, or tortuous, as size and relative dimensions may require.

Across pathway 13, and in a more or less exactly radial direction (preferably exactly radial) with respect to the axis of rotation of the structure, extends a runway 3. In this runway is arranged a movable member 6, which under centrifugal force of the projectile in flight tends to move to the outer end of the runway, but which is normally held at the inner end by a pair of spring-back centrifugally releasing bolts 4, precisely such as are described in my co-pending application named above. The movable member 6 is preferably recessed to receive

the bolts, in the manner illustrated in the drawings, and as described in the application referred to. When the movable member 6 is retracted and stands in the locked position shown in Fig. 1, the pathway for detonation transmission is interrupted, so that the explosion of detonator D (should it prematurely occur) cannot be imparted to fire the charge B; but when bolts 4 recede, unlocking member 6, and when member 6 slides outward under centrifugal force, a detonation pathway in its body is brought into register with the previously interrupted pathway 13, and then the continuity of the pathway is established from detonator D to burster charge B. The portion of the pathway which is formed in the body of member 6 may conveniently encircle the member 6 being in this case a filling of detonation transmitting material packed or molded into the encircling groove 12, which has this advantage: However the member 6 may turn on its own axis, registry of the portion of the pathway formed in member 6 with the portion of the pathway formed in the partition wall and indicated 13 will be certain when the movable member is shifted in the manner and to the ends described.

A locking member 7 may lie within the inner end of member 6; and, by extending the runway 3 across the center of rotation, this locking member 7 will under centrifugal force crowd against the inner end of the runway and be retracted from member 6 as that member moves outward, and then having escaped from the recess which held it, it may so move (by special shaping, if found necessary) that it will no longer stand alined with the recess, but will thereafter serve as a locking block, to prevent return of the member 6, now moved to armed position. The locking member specifically illustrated in Fig. 3 is merely exemplary. It is so shaped (having an oblique rear surface) that when fully withdrawn from the member 6 it will tip and will not again be in a position to reenter the recess which formerly contained it.

The pathway for the transmission of detonation from detonator to burster charge may be such as the intelligent designer may select; it must be of material suitable for detonation transmission; as shown (and this is my preference) it is a narrow duct filled with high explosive (preferably tri-nitro-toluene); and, furthermore, the groove in the movable member 6 is in like manner filled with high explosive. When the duct and groove are brought to register one with the other, there is formed a continuous line for detonation transmission.

The pathway for detonation transmission from detonator to burster charge consisting of a column of such material as tri-nitro-toluene cannot be penetrated by a flash; ig-

nition started at one end cannot burn through. Furthermore, thin septa of metal, if interposed and dividing the column at intervals—though manifestly they would cut off any bodily advance of flame—would not prevent transmission of detonation.

I claim as my invention:

1. In an explosive projectile the combination of a burster charge of high explosive, a detonator, a path of detonation transmission extending from said detonator to said burster charge, and means for alternately interrupting and making continuous said path.
- 15 2. In an explosive projectile the combination of a burster charge of high explosive, a detonator, a train of detonation transmission extending from said detonator to said burster charge a section of said train being movable from a position of interruption to a position of continuity.
- 25 3. In an explosive projectile the combination of a burster charge of high explosive, a detonator, a path of detonation transmission extending from said detonator to said burster charge and normally discontinuous, a member movable in sequence on the firing of the projectile from a gun for establishing the continuity of said path, and means for 30 preventing retrogression of said movable member.
- 35 4. In an explosive projectile the combination of a burster charge, a detonator, a path of detonation transmission leading from said detonator to said burster charge, a break in said path, a member movable in such break and responsive within the range of such movement to centrifugal force exerted upon it on the flight of the projectile from a rifled 40 gun, a centrifugally opening lock normally holding said movable member at one end of the range of its movement, and a centrifugally closing lock for said movable member at the opposite end of its range.
- 45 5. In an explosive projectile the combination of a burster charge, a safety chamber, a detonator stationary with relation to and adjacent said safety chamber and removed at an interval from said burster charge, a 50 path of detonation transmission leading from said detonator to said burster charge, said path being normally interrupted, and means for establishing the continuity of said path.
- 55 6. In an explosive projectile the combination of a burster charge, a closed safety chamber, a detonator adjacent said safety chamber, a path of detonation transmission normally interrupted extending from said

detonator to said burster charge, and means 60 for establishing the continuity of said path.

7. In an explosive projectile the combination of a burster charge, a detonator, an ignition cap, an ignition path from said cap to said detonator, a normally interrupted path 65 of detonation transmission from said detonator to said burster charge, and means for establishing the continuity of said path of detonation transmission.

8. A fuse stock for an explosive projectile 70 including a substantially cylindrical body divided by a transverse partition wall, a detonator within a safety chamber arranged together with its ignition cap on one side of said wall, a reinforcing charge arranged on 75 the opposite side of said wall, a centrifugal bolt movable in a transverse runway in said wall, and a column of detonation-transmitting material contained in part in said wall and in part in said bolt.

9. In a projectile the combination with a burster charge, a source of detonation, and a path of detonation transmission from said source to said burster charge, of a cylindrical bolt movable in a runway across said detonation transmission path said bolt being provided with an encircling path of detonation transmission.

10. In a projectile the combination with a burster charge, a source of detonation, and a path of detonation transmission from said source to said burster charge, of a runway intersecting said detonation transmission path and extending across the center of rotation of said projectile when fired from a 95 rifled gun and a two part bolt arranged in said runway, the parts of said bolt normally telescoped one upon the other but extensible under centrifugal force when the projectile is rotated, the said bolt parts when fully extended being relatively movable to positions forbidding retraction.

11. In an explosive projectile a burster charge of high explosive arranged within the projectile and in its shape consisting of 105 a larger main body and an attenuated extension, and, in combination with the burster charge so shaped, a detonator arranged at the remote end of said extension, and a make-and-break device, arranged in said extension of the burster charge.

In testimony whereof I have hereunto set my hand.

JOHN B. SEMPLE.
